METHOD OF TREATING GASOLINE WITH CITRIC ACID TO REMOVE COPPER

John W. Thompson, Kingsport, Tenn., assignor to Eastman Kodak Company, Rochester, N. Y., a corporation of New Jersey

No Drawing. Application March 28, 1952,
Serial No. 279,211

1 Claim. (Cl. 196—39)

This invention relates to a method of improving the quality of petroleum hydrocarbons, and more particularly, to improving the quality of petroleum hydrocarbons which have been treated with copper-containing reagents for the removal or conversion of sulfur compounds.

It is well known to remove sulfur compounds, such as mercaptans, from petroleum hydrocarbons, such as gasoline motor fuels, or to convert such mercaptans into less objectionable compounds by appropriate chemical treatment, generally referred to as a sweetening operation. One quite common method of sweetening involves the use of a doctor solution made from sodium hydroxide and lead oxide. Treatment of the sour gasoline with this solution and added sulfur converts the mercaptans to alkyl disulfides. The amount of sulfur used must be very carefully controlled since excess sulfur in the gasoline is harmful with respect to corrosiveness, lead susceptibility and inhibitor susceptibility. On the other hand, the use of insufficient sulfur causes lead mercaptides to be left in the fuel.

Instead of using the doctor solution method, it has been previously proposed to substitute other sweetening operations employing copper salts for the purpose of removing the sulfur compounds or converting them into less objectionable substances. This operation is widely used for the treatment of petroleum motor fuels, such as gasoline. Frequently in the copper sweetening process various copper compounds may be carried over into the treated gasoline where they are very objectionable since even in trace concentrations they catalyze oxidative deterioration of the treated hydrocarbon. This difficulty is somewhat alleviated through the use of the known antioxidants, although the amount of improvement is not great enough to completely overcome the objections noted above. It is, therefore, desirable to provide some method which would substantially completely remove all heavy metal compounds from the petroleum hydrocarbon, thus allowing the antioxidant to function at its fullest efficiency.

It is, therefore, an object of my invention to provide an improved method of removing metals, such as copper, from petroleum hydrocarbons. Another object is to render petroleum hydrocarbons, such as cracked gasoline, more stable to oxidative deterioration catalyzed by metals and to permit more effective use of gasoline antioxidants.

Still another object is to provide a class of new and effective treating agents for removing such metals from petroleum hydrocarbons, such as cracked gasoline. Other objects will become apparent from a consideration of the following description and examples.

According to my invention, I provide the novel effects mentioned above by treating a petroleum hydrocarbon which has been sweetened with reagents containing copper with a solution containing certain types of aliphatic carboxylic acids. The aliphatic carboxylic acids which are useful in practicing my invention comprise aliphatic hydroxy monocarboxylic acids, such as lactic, glycolic, α -hydroxy isobutyric acids, etc., and aliphatic polycar-

2

boxylic acids selected from those represented by the following general formula:

5 (I)

wherein R, R₁, R₂, R₃, R₄ and R₅ each represents a member selected from the group consisting of a hydrogen atom, a hydroxyl group, a carboxyl group, an alkyl group (e. g. methyl, ethyl, etc.), and an aryl group (e. g. phenyl, o-, m-, and p-tolyl, etc.), and a, b and c each represents a positive integer of from 1 to 2. Typical polycarboxylic acids included within the scope of Formula I given above comprise oxalic acid, citric acid, tartaric acid, malonic acid, succinic acid, tricarboxylic acid, etc. The aliphatic carboxylic acids which have been found to be most useful in practicing my invention comprise those acids containing only carbon, hydrogen and oxygen atoms.

Advantageously, the petroleum hydrocarbon which has been treated with a copper-containing reagent is washed with an aqueous solution of one of the aliphatic carboxylic acids of my invention. The aliphatic carboxylic acid reacts with the residual copper reagent in the petroleum hydrocarbon and substantially completely removes said copper reagent from the treated hydrocarbon. Since the reaction product between the copper reagent and the aliphatic carboxylic acid has a higher solubility in the water than it has in the petroleum hydrocarbon, it is dissolved in the water, thus leaving the petroleum hydrocarbon substantially free of copper reagent. Efficient mixing between the aqueous solution containing the aliphatic carboxylic acid and the petroleum hydrocarbon assures substantially complete removal of the copper reagent.

The aqueous reagent solution contains one or more of the aliphatic carboxylic acids and the concentration of acid can be varied according to the petroleum hydrocarbon being treated. Generally, a solution of from 0.1 up to the weight percent required for a saturated solution of acid in water is effective for the purposes of my invention.

45 The process of my invention can be carried out in any suitable manner, such as a batch or continuous type operation, wherein suitable contact of petroleum hydrocarbon and washing solution can be had. As an example of one possible method, the washing solution and petroleum hydrocarbon, such as cracked gasoline, are intimately mixed in one chamber and the mixture allowed to settle either in the same or another vessel. After separation into two layers, the upper layer comprising the petroleum hydrocarbon, now substantially free of metal content, is withdrawn for further treatment or disposal as required. In some instances, it may be felt desirable to further wash the gasoline with water to remove any other remaining traces of washing solution, although tests have shown an after treatment with water to be unnecessary. Apparently, the contrasting high solubility of the acids in water and insolubility in the petroleum hydrocarbon insures very little acid being left in the petroleum hydrocarbon. The lower reagent solution can be withdrawn and recycled in the process until disposal is indicated by high metal content.

60 Instead of using an aqueous solution of the aliphatic carboxylic acid, a solution of the acid in an organic solvent can be employed. When an organic solvent is desired, it is advantageously selected so that it is a solvent for the aliphatic carboxylic acid but has little or no solubility in the petroleum hydrocarbon. It is thus possible to effectively separate the organic solvent

solution containing the aliphatic carboxylic acid from the treated petroleum hydrocarbon.

After treatment of the petroleum hydrocarbon with the solution containing the aliphatic carboxylic acid, the treated petroleum hydrocarbon can then be stabilized against oxidative deterioration by addition of one or more of the known antioxidants ordinarily used for this purpose. Such antioxidants comprise, for example, the p-amino-phenols, hydroquinones, p-phenylenediamines, etc. See,

In the column under Induction Period After Washing, Sample+Cu+BAP+Water, the induction period in minutes is given for the sample which has been washed with the solution containing the aliphatic carboxylic acid, the treated gasoline being further washed with de-ionized water before addition of the antioxidant, BAP. This last mentioned column shows that no improvement is ordinarily obtained by the additional water washing step.

The results obtained were as follows:

Effectiveness of organic acids in washing copper from gasoline

SECTION A

Sample No.	Induction Period Before Washing				Induction Period After Washing				Effectiveness, percent
	Blank	Sample+Cu	Sample+BAP	Sample+Cu+BAP	Washing Agent	Sample+Cu	Sample+Cu+BAP	Sample+Cu+BAP+Water	
1.....	95	55	515	167	water.....		410	540	70
2.....	100	57	525	185	citric acid.....		555	540	100+
3.....	100	57	530	185	d-tartaric acid.....	100	547	537	100+
4.....	95	55	517	160	malonic acid.....		547	550	100+
5.....	95	55	515	167	oxalic acid.....		535	.....	100+

SECTION B

6.....	95	45	512	60	water.....	55	65	.....	4
7.....	95	45	512	60	citric acid.....	130	497	.....	97

for example, Brimer U. S. Patent 2,496,930, issued February 7, 1950, von Bramer et al. U. S. Patent 2,323,948, issued July 13, 1943, etc.

The efficiency of the solution containing the aliphatic carboxylic acid in removing the heavy metal, such as copper, from the petroleum hydrocarbon, such as cracked gasoline, was determined by means of oxygen bomb stability tests on unwashed and solution-washed samples of copper containing cracked gasoline, which were inhibited with a gasoline antioxidant just prior to testing. Simultaneously, control tests were made on the cracked gasoline containing various combinations of copper and antioxidant. In the examples described below, the copper was added in the form of a benzene solution of copper oleate and the antioxidant used was N-n-butyl-p-aminophenol, although other antioxidants were found to be equally effective for demonstrating the results of my invention. The washing consisted of shaking the cracked gasoline with 10 volume percent of a 10 weight percent aqueous aliphatic carboxylic acid solution for 5 minutes in a separatory funnel. The treated cracked gasoline was removed and then tested by means of an oxygen bomb stability test.

In the oxygen bomb stability test, 200 cc. samples of gasoline in glass bottles were heated at 100° C. in stainless steel bombs under 100 p. s. i. oxygen pressure. The induction period of the gasoline was measured as the time in minutes before rapid oxidation of the gasoline began, as evidenced by a sharp drop in oxygen pressure.

The following table illustrates the effect of various solutions of aliphatic carboxylic acids in removing the copper from the cracked gasoline. In section A of the table, an amount of copper oleate was employed sufficient to give an equivalent of 1.0 mg. of copper per liter, while in section B, an amount of copper oleate was employed in an amount sufficient to give 5.0 mg. of copper per liter. The abbreviation BAP stands for N-n-butyl-p-aminophenol. The induction period in minutes is given before washing with the aqueous solution containing the aliphatic carboxylic acid, and similar data are given for the cracked gasoline after washing. The effectiveness in percent of the particular washing agent is given in the last column, the figure being obtained according to the equation:

$$\text{Effectiveness} = \frac{\left(\frac{\text{Induction period of unwashed gasoline containing BAP+Cu}}{\text{Induction period of washed gasoline containing BAP+Cu}} \right) - 1}{\left(\frac{\text{Induction period of unwashed gasoline containing BAP}}{\text{Induction period of washed gasoline containing BAP}} \right) - 1} \times 100$$

The purpose of section B in the above table is to show that while water alone does effectively remove some residual copper sweetening agent when the concentration of the agent is low, as is true in section A, this is by no means the case when the concentration of residual copper sweetening agent is higher, such as might ordinarily be encountered in the treatment of cracked gasoline, as is true in section B. The citric acid used in arriving at the results given in the table was employed as the monohydrate. The concentration of the BAP where indicated in the above table was 0.0048 weight percent. The particular gasolines employed were a Pennsylvania cracked gasoline consisting of a blend of catalytically-cracked and thermally-cracked fuels.

The above table is believed to clearly show that the aliphatic carboxylic acids of my invention effectively reduce the amount of copper sweetening agent in the cracked gasoline to such an extent that the conventional gasoline antioxidants can stabilize the fuel in the desired manner. It will be noted, for example, from the table that while sample No. 7 gave an effectiveness of 97 percent, i. e., the treatment with the solution of citric acid returned the induction period to within 97 percent of that obtained when the gasoline was completely free of copper oleate, sample No. 6 gave a corresponding induction period return of only 4 percent.

What I claim as my invention and desire secured by Letters Patent of the United States is:

A process of stabilizing cracked gasoline which has been sweetened with a copper-containing reagent which comprises intimately mixing said cracked gasoline with an aqueous solution containing from 0.1 up to the weight percent required for a saturated solution in water of citric acid, and separating said cracked gasoline from said aqueous solution containing the citric acid.
